DESIGN FOR A COMBINED LAMP PULL CORD AND THERMOMETER

Samuel Lapin, New York, N. Y.

Application October 20, 1938, Serial No. 80,570

Term of patent 3½ years

To all whom it may concern:

Be it known that I, Samuel Lapin, a citizen of the United States, residing at New York city, New York, county and State of New York, have invented a new, original, and ornamental Design for a Combined Lamp Pull Cord and Thermometer, of which the following is a specification, reference being had to the accompanying drawing, forming part thereof.

Fig. 1 is a front elevational view of a combined

lamp pull cord and thermometer, showing my new design.

Fig. 2 is a side elevational view and

Fig. 3 is a rear elevational view thereof.

I claim:

The ornamental design for a combined lamp pull cord and thermometer, substantially as shown.

SAMUEL LAPIN.
